FIG. 1.

FIG. 3.

FIG. 2.

FIG. 4.

FIG. 5.

FIG. 1 is a front elevational view of a pendant or similar article showing our new design;

FIG. 2 is a side elevational view;

FIG. 3 is a top view;

FIG. 4 is a bottom view; and

FIG. 5 is a front elevational view of our design of FIG. 1 wherein the cap is split into a plurality of fingers.

The characteristic feature of our design resides in the particular heart-shaped outline of twisted wire in combination with a capped tooth-like object depending from the interior cleft of the heart, substantially as shown.

We claim:

The ornamental design for a pendant or similar article, as shown and described.
